ARTICLE HANDLING APPARATUS

Harry E. Andrews, Horace E. Comer, and
Donald M. Brown, Phoenix, Ariz.

Application June 29, 1953, Serial No. 364,782

10 Claims. (Cl. 198—144)

1

This invention relates generally to article handling, and pertains more particularly to improved apparatus primarily directed to expediting the handling of articles while requiring a minimum of floor space.

An object of this invention is to provide an improved article handling apparatus enabling the production packing of large amounts of commodities in a small area of small space with a minimum of hand labor.

Another object of this invention is to provide an improved apparatus for handling articles which is so designed and constructed as to be readily adaptable to numerous types of articles.

Another object of this invention is to provide an improved article handling apparatus which operates in a closed or continuous cycle and is constructed of polygonal configuration for presenting a series of alternate input and discharge stations.

Another object of this invention is to provide an improved form of article handling apparatus which incorporates the use of pivotally suspended buckets and operatively associated cam means for positioning the buckets in proper relation at the discharge stations for ejection of the commodities disposed within the buckets.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

Figure 1 is a plan view of an article handling apparatus constructed in accordance with this invention;

Figure 2 is a side elevational view of the assembly shown in Figure 1;

Figure 3 is a vertical section taken substantially along the plane of section line 3—3 of Figure 1;

Figure 4 is a vertical section taken substantially along the section line 4—4 of Figure 3;

Figure 5 is an enlarged plan view partially in section showing one corner of the main frame of the apparatus;

Figure 6 is a longitudinal section taken through one of the bucket members;

Figure 7 is an elevational view showing the chain slack take-up mechanism;

Figure 8 is a vertical section taken substantially along the plane of section line 8—8 of Figure 7; and

2

Figure 9 is a perspective view of the reinforcing plate shown in Figures 7 and 8.

Referring now more particularly to Figure 1, reference numeral 10 indicates generally the main frame or trackway portion of the machine which may be of substantially rectangular configuration and whose opposite sides 12 and 14 present input stations, while the other sides 16 and 18 present discharge stations, in a manner presently apparent. Each corner of the frame is provided with a sprocket wheel 20 and it will be readily appreciated that one of these sprocket wheels is driven by any suitable means, such as an electric motor or the like, so as to move the chain member 22 in a clockwise fashion about the frame.

Referring now more particularly to Figures 2 and 3, it will be seen that the frame or trackway 10 consists of channel members 24 and 26 which are disposed in back-to-back relation and are slightly spaced in the manner shown to provide a trackway therebetween which receives the chain 22, as will be readily appreciated. These channel members are suitably secured to the upper end of the various support post members 28 which maintain the frame in an elevated position with respect to the supporting floor surface. It will be readily appreciated that the frame 10 need not necessarily be positively connected to the support members 28 but may merely rest thereon since the weight of the assembly is such as to allow this manner of positioning the frame.

Corner pieces 30 are provided at each corner of the frame for securing the various channel members together to maintain the rectangular configuration of the frame, but it is to be noted that the frame is split, as indicated by the reference character 32, at opposite sides at the input stations thereof. As seen most clearly in Figures 7—9, the abutting portions of the frame 10 are supported by the reinforcing plate 34 which is suitably secured by fastening bolts 36 to one abutting end of the frame for projection therefrom beneath the other abutting end thereof. The reinforcing plate 34 is provided with elongated slots 38 through which the fastening bolts 36 project so that the plate may be projected farther from the frame end to which it is secured beneath the other abutting frame end, the reinforcing plate 30 to properly align the frame section. Each frame end is provided with bracket plate members 40 which are suitably apertured for reception of the adjusting bolt 42 which is provided with the lock nut members 44, 46 and 48 in the manner shown, so that the adjacent

ends of the frame sections may be spaced more or less to increase the area of the frame when it is necessary to take up slack in the chain member 22 for proper tensioning of the same.

Referring now more particularly to Figures 2-4, it will be seen that the chain 22 has suitably secured thereto at longitudinally spaced points therealong a number of uprights 50 which are provided at their upper ends with the cross-arms 52 for extension beyond the confines of the channel members 24 and 26 in the manner shown. The manner of securement of the uprights 50 to the chains 22 may be through the medium of pins 54 rigidly secured to portions of the chain and snugly received within a lower recessed end of the uprights. The bucket members indicated generally by the reference character 56 are provided at their upper or open end with the bracket ears 58 which are apertured to receive the reduced end portions 80 of the cross-arms and the double lock nut assembly 62 maintains these bucket members on the cross-arm though pivotally suspended therefrom.

The uprights 50 are provided adjacent their lower end with the ball bearing members 64 whose diameter is slightly less than the width between the web of the channel members 24 and 26, the purpose of this construction being to assure vertical positioning of the uprights 50. Additionally, the guide members 66 and 68 are provided at opposite sides of the uprights 50, being secured as by the posts 70 to respective channel members, and it will be noted that wherever the guide members are interrupted, the adjacent ends of the succeeding guide members in the direction of travel of the bucket members are outwardly flared as indicated by the reference character 72 so as to make absolutely certain that the uprights are properly guided with respect to the trackways.

Since the weight of the bucket members and their manner of suspension from the cross-arms 52 is such as to tip the uprights 50 in a direction opposite the direction of travel of the chain 22, the brace rods 74 are provided which are rigidly secured at their upper ends to the uprights 50 and are provided at their lower ends with the bearing plate members 76 resting upon the chains 22 in the manner shown, additional cross-brace members 78 being provided for imparting absolute rigidity to the assembly. To lend support to the chain 22 between the sprocket members 28, the strips 80 are provided directly therebeneath in the manner shown so as to support the intermediate portions of the chain and prevent its sagging.

Referring now more particularly to Figures 2, 3 and 6, it will be seen that each of the bucket members 56 is provided at its forward or open end with a belled or flared mouth 82 and that its rearward end is tapered as indicated by the reference character 84 and provided with the cover member 86 pivoted to the bucket. Each bucket is of generally circular configuration and is formed by bending a sheet of material in circular fashion but leaving the adjacent end 88 in slightly spaced relation so as to provide a longitudinally extending slot at the lower portion of each bucket. The inner side of each bucket is provided with a laterally extending rod 90 which has journaled on its free end a roller 92 which is engageable with the cam mechanism indicated generally by the reference character 94 and which includes the inclined or ramp portion 96, the initial horizontal portion 98 and the horizontal guide portion 100. Intermediate the ex-

tent of the horizontal guide portion 100, the frame is provided with a support member 102 extending outwardly on either side thereof to form a support or base for the upright bracket arms 104 which carry the substantially circular ejector plates 106 at their upper ends. It will be seen that the ejector plates 106 are of slightly less diameter than the internal diameter of the buckets 56 so that the plates may readily pass therethrough, the belled or flared mouths of the bucket members ensuring proper projection of the plate within the bucket. Of course, the bracket arms 104 are in register with the longitudinal slots in the lower portion of the buckets, as shown most clearly in Figure 3.

In operation, operators will be positioned at the input station sides 12 and 14 of the assembly for feeding commodities into the bucket members, in this respect, it being noted that the operators may double up at each input side of the machine, that is, one inside and one outside, without fear of interference with one another. It is preferred that the cover members 86 of each bucket be spring loaded or weighted so as to prevent the weight of the commodity from opening these cover members, it being appreciated that the taper or angularity 84 on the rearward portion of each bucket is such that the weight of the cover members 86 tends to operate in a closing fashion in the normal free suspended position of the bucket having the commodities disposed therein. The buckets pass around the trackway under influence of the chain 22 until their rollers 92 engage the inclined ramp portion 96 of the cam assembly 94 which will elevate the buckets to a horizontal position, as shown in Figure 2, until they are received in the horizontal guide portions 100 which are formed to partially surround the rollers 92 and prevent lateral shifting of the buckets so that they are positively aligned with the ejector plates 106. At any convenient point, the sack or bag members 108 are slipped over the rearward end of the bucket so that when the ejector plates force the commodities outwardly of the buckets, the commodities will be bagged, the bags dropping to a suitable conveyor belt (not shown) beneath the frame assembly 16 for transportation to a desired location. Of course, it will be clear that the tapering configuration of the rearward portion of each of the buckets enables the bag members 108 to be easily slid thereon.

For the purpose of simplicity, only a few bucket members are shown on the chain 22, but it is to be understood that the entire extent thereof is so provided.

From the foregoing, the construction and operation of the device will be readily understood and further explanation is believed to be unnecessary. However, since numerous modifications and changes will readily occur to those skilled in the art, it is not desired to limit the invention to the exact construction shown and described, and accordingly, all suitable modifications and equivalents may be resorted to, falling within the scope of the appended claims.

What is claimed as new is as follows:

1. A device for conveying articles comprising, a closed trackway having alternate input and discharge stations at spaced points therealong, means for carrying commodities along said trackway, means for moving the first means, and means for automatically discharging commodities loaded in the first means at the input station 70 from the same at said discharge stations, the

second mentioned means including an endless flexible element disposed in vertically spaced relation to said trackway, said first means including bucket members pivotally carried adjacent their open ends by said flexible element and provided at their other ends with hinged covers, said bucket members being suspended normally in an angular position, and means at said discharge stations for elevating said bucket members to a horizontal position.

2. A device for conveying articles comprising, a closed trackway having alternate input and discharge stations at spaced points therealong, means for carrying commodities along said trackway, means for moving the first means, and means for automatically discharging commodities loaded in the first means at the input station from the same at said discharge stations, the first means including bucket members pivotally suspended adjacent their open ends and provided at their other ends with hinged covers, said bucket members being suspended normally in an angular position, and means at said discharge stations for elevating said bucket members to a horizontal position, the last mentioned means including a cam track adjacent said trackway.

3. A device for conveying articles comprising, a closed trackway having alternate input and discharge stations at spaced points therealong, means for carrying commodities along said trackway, means for moving the first means, and means for automatically discharging commodities loaded in the first means at the input station from the same at said discharge stations, the first means including bucket members pivotally suspended adjacent their open ends and provided at their other ends with hinged covers, said bucket members being suspended normally in an angular position, and means at said discharge stations for elevating said bucket members to a horizontal position, said bucket members being longitudinally split, and the last mentioned means including an ejector member disposed in the path of movement of said bucket members for passage therethrough, said ejector members being supported by bracket arms of less width than the split in said bucket members enabling the arms to pass therethrough.

4. In a commodity handling apparatus, a rectangular frame formed by a pair of spaced channel members placed in back-to-back relation, a sprocket disposed at each corner of said frame, a chain trained over said sprockets and passing between said channel members, a series of uprights secured to said chain at longitudinally spaced points therealong, a cross-arm secured

to the upper end of each of said uprights, bucket members pivotally suspended from said cross-arms, cam tracks positioned at opposite sides of said frame, ejector means positioned at said opposite side of the frame, means on said bucket members engageable with said cam tracks for positioning the bucket members for operation by said ejector means, whereby articles disposed in said bucket members at the other sides of said frame will be ejected at said opposite sides of the frame.

5. The combination of claim 4 wherein said means comprises rollers carried laterally of said bucket members.

15 6. The combination of claim 4 wherein certain of said pairs of channel members are extensibly interconnected for effecting slack take-up on said chains.

7. The combination of claim 4 wherein guide members are provided in vertically spaced relation to each of said channel members for guidably receiving said uprights therebetween.

20 8. The combination of claim 4 wherein said bucket members are pivotally suspended adjacent their open ends and are provided at their opposite ends with hinged covers, said bucket members being suspended normally in an angular position, said cam tracks operating to dispose said bucket members in a horizontal position.

9. The combination of claim 8 wherein said bucket members are split to present longitudinal slots, said ejector means being supported by bracket arms of less width than said slots enabling the arms to pass therethrough.

35 10. A device for conveying articles comprising, a closed trackway having alternate input and discharge stations at spaced points therealong, means for carrying commodities along said trackway, means for moving the first means, said first means including bucket members pivotally suspended adjacent their open ends and provided at their other ends with hinged covers, said bucket members being suspended normally in an angular position, means at said discharge stations for elevating said bucket members to a horizontal position, and means at said discharge stations operable when said buckets are disposed horizontally to automatically discharge commodities therefrom.
